(57) **CLAIM**

The ornamental design for a display screen with a graphical user interface with a transitional icon, as shown and described.

DESCRIPTION

FIG. 1 is a first image in a sequence of a display screen with a graphical user interface with a transitional icon, showing the new design;

FIG. 2 is a second image thereof;

FIG. 3 is a third image thereof;

FIG. 4 is a fourth image thereof;

FIG. 5 is a fifth image thereof;

FIG. 6 is a sixth image thereof;

FIG. 7 is a seventh image thereof;

FIG. 8 is a eighth image thereof;

FIG. 9 is a ninth image thereof;

FIG. 10 is a tenth image thereof;

FIG. 11 is a eleventh image thereof;

FIG. 12 is a twelfth image thereof;

FIG. 13 is a thirteenth image thereof;

FIG. 14 is a fourteenth image thereof;

FIG. 15 is a fifteenth image thereof;

FIG. 16 is a sixteenth image thereof;

FIG. 17 is a seventeenth image thereof;

FIG. 18 is a eighteenth image thereof;

FIG. 19 is a nineteenth image thereof; and,

FIG. 20 is a twentieth image thereof.

The appearance of the transitional icon sequentially transitions between the images shown in FIGS. 1-20.

The process or period in which one image transitions to another image forms no part of the claimed design.

The broken lines shown in the drawings illustrate a display screen, and form no part of the claimed design.

The shaded areas of the drawings show a contrast in appearance.
